GAME BOARD

Margarethe Plaumann, Schuberstrasse 1,
D-6450 Hanau (Main), Germany

Filed Oct. 2, 1974, Ser. No. 511,394

Claims priority, application Germany Apr. 10, 1974

Term of patent 14 years

Int. Cl. D21—01

U.S. Cl. D34—5 SS

FIG. 1 is a top plan view of a game board showing my new design.

The bottom and sides of the game board, not shown, are plain and unornamented, and the board is of conventional thickness.

I claim:

The ornamental design for a game board, as shown and described.
